S. Thomas

ATTORNEY.

UNITED STATES PATENT OFFICE.

JOHN J. ESPER, OF DEARBORN, MICHIGAN.

SPINNING TOP.

Application filed March 18, 1926. Serial No. 95,739.

My invention relates to spinning tops shown in the accompanying drawings and more particularly described in the following specification and claims.

5 This invention is designed as an improvement on the spinning top shown and described in my Patent #1,559,232 dated October 27th, 1925, and its primary object is to simplify the construction and operation of 10 the earlier device and to reduce the manufacturing cost.

One feature of the present invention consists in providing a wire spring coiled upon its spindle and connected at the lower end 15 with a flange integral therewith:—the upper end of the spring having a hook-shaped formation adapted to enter an aperture in the body of the top:—the construction being such that the upper end of the spring may 20 be automatically released from clutched connection with the body portion synchronously with the release of the ratchet from the dog controlling the latter to spin the top,—that the driving spring may not be broken in case 25 the operator should continue gripping the spindle against the expanding action of the driving spring.

A further object is to simplify my former 30 invention by eliminating the spring and other working parts contained within the knob at the upper end of the spindle,—all working parts being now entirely housed within the body of the top.

With the foregoing and other objects in 35 view which will appear as the description proceeds the invention further resides in the combination and arrangement of parts and in the details of construction hereinafter described and claimed it being understood that 40 changes may be made in the precise embodiment of the invention herein disclosed without departing from the spirit of the same.

In the drawings accompanying this specification:

45 Figure 1 is a vertical cross sectional view through the top, showing a portion of its tubular spindle broken away and a dog engaging a ratchet member carried by the spindle when winding the driving spring.

50 Figure 2 is a similar cross sectional view showing the spindle pushed downwardly to the limit of its movement whereby the ratchet mechanism is released,—as when starting the top.

55 Figure 3 is a fragmentary horizontal sectional view taken on or about line 3—3 of

Figure 1 showing the ratchet integral with the wall of the spindle, engaged by its spring controlled dog.

Figure 4 is a fragmentary vertical cross 60 sectional view through the upper part of the top, showing an opening in a partition of the top body to receive the upper hooked end of the driving spring, and in dotted lines the hooked end of the spring released 65 from engagement with the partition wall.

Figure 5 is a detail view of the partition wall showing the openings in the plate with which the hooked end of the driving spring 70 may engage, also the peripheral notches through which lugs struck up from the body of the top enter to secure the partition in place and to prevent its rotation with reference to the wall of the top.

Referring now to the letters of reference 75 placed upon the drawings:

A and A¹ denote the body of the top, preferably formed of sheet metal connected together by an overlapping joint A².

B indicates a pivot pin extending through 80 the body of the top to receive the end of a tubular rotatable and longitudinally movable spindle C projecting upwardly through the body of the top,—provided with a flange a, forming a bearing for the spindle.

85 D is a knob formed of two telescoping parts fitted to the projecting end of the spindle for convenience in manually rotating the latter.

E denotes a spirally coiled spring preferably formed of wire sleeved upon the spindle, its lower end being bent to enter an aperture in a flange C^a at the lower end of the spindle. If desired however, the spring 90 may be engaged directly to the spindle.

95 F is a partition wall provided with a central aperture for the passage of the spindle, with its perimeter notched at f to receive a plurality of inwardly bent lugs a¹ struck from the body of the top.

100 The upper end of the driving spring is provided with a hook-shaped end E^a adapted to enter covered apertures f¹ f¹ provided in the partition wall F, the construction being such, however, that the hook will readily free itself from the aperture when the top is spinning and as readily enter the openings in the partition when it is desired to manually wind the top.

105 In the chamber formed between the partition wall and the body of the top, is a ratchet wheel G preferably integral with the

spindle, adapted to be engaged by a dog H under the urge of a spring I, one end of which bears on the dog,—the other end being secured to the partition wall.

5 The central opening through the partition is of sufficient size to permit the passage of the ratchet wheel when the spindle is shifted to release the ratchet from the control of the dog.

10 Having now indicated the several parts by reference letters the construction and operation of the device will be readily understood:

To wind the top the operator grasps the body portion in one hand and the knob at the end of the spindle with the other, pulling the spindle outwardly until the ratchet wheel G is brought into engagement with the spring actuated dog H, as indicated in

15 Figure 1 of the drawings. The operator may then "wind up the spring." Upon the completion of the winding operation the operator, while still grasping the knob, forces the pointed end of the pivot pin upon the 20 floor or other surface upon which the top is to be spun. This action causes the spindle to move downwardly releasing the ratchet wheel G from engagement with the dog

H, whereupon the driving spring will cause 25 the top to rotate;—the upper hooked end of the spring releasing itself from engagement with the partition wall, thereby relieving the spring of any tendency to snap resulting from the operator holding the knob

30 while the top is turning. The spring expands energy in rotating the top while the spindle is being held by the hand of the operator and the releasing of the spring from the body of the top prevents the 35 rotation of the top from unwinding the spring beyond its normal unwound condition.

Having thus described my invention what I claim is:

1. In a spinning top; a chambered body; 45 a pivot pin projecting through the lower wall of the top; a longitudinally movable rotatable spindle projecting through the upper wall of the top; a knob fitted to the outer end of the spindle; a ratchet carried 50 by the spindle; a dog adapted to engage the ratchet; and a coiled driving spring sleeved upon the spindle and fixedly secured to the latter at one end, the opposite end of the spring being adapted for automatic engagement or disengagement with co-ordinating means provided in the wall of the top, whereby the spring may be held when manually wound, and upon shifting the spindle longitudinally it may be automatically released concomitantly with the spinning of the top by the spring.

2. In a spinning top; a chambered body; a pivot pin projecting through the lower wall of the top with a short upstanding stub portion extending into the chambered body; 65 a longitudinally movable rotatable spindle having its lower end sleeved upon the stub of the pivot pin and its upper end projecting through the wall of the top; a knob fitted to the outer end of the spindle; a ratchet carried by the spindle; a partition wall secured to the body of the top having a central opening for the spindle and ratchet when the spindle is longitudinally shifted; a spring actuated dog pivoted to 70 the partition wall adapted to engage said ratchet; a coiled spring sleeved upon the spindle and fixedly secured to the latter at one end, the opposite end of the spring having a hook-shaped formation adapted to 75 enter an aperture in the partition wall, whereby it may be automatically clutched thereto—when the spring is manually wound—or released respectively therefrom upon shifting the spindle longitudinally to 80 disengage the ratchet from engagement with the spring actuated dog to enable the spring to rotate the body of the top and be automatically released therefrom.

3. In a spinning top; a chambered body; 90 a pivot pin projecting through the lower wall of the top having a short upstanding stub portion extending into the chambered body; a longitudinally movable rotatable spindle sleeved upon the stub of the pivot 95 pin and provided with an outstanding flange integral with the spindle, said spindle extending through the upper wall of the top; a knob fitted to the outer end of the spindle; a partition wall having a central 100 opening for the passage of the spindle with notches around its outer perimeter to receive lugs struck from the wall of the body and bent to enter said notches, whereby the partition is held in position, and against rotation; a coiled wire driving spring sleeved upon the spindle having one end permanently engaged to the flange of the spindle, the opposite end of the spring having a hook adapted to enter a covered aperture 110 formed in the partition wall to receive it, whereby the spring may be automatically clutched to, or released from said partition wall; ratchet teeth integral with the spindle; and a spring actuated dog pivoted 115 to the partition wall, adapted to engage said ratchet teeth and to be released from engagement therewith upon manually shifting the spindle longitudinally.

In testimony whereof, I sign this specification.

JOHN J. ESPER.
